UNITED STATES PATENT OFFICE

112,966

DESIGN FOR AN INDICATING KNOB

Herbert F. Sammons, Chicago, Ill., assignor to Crane Co., Chicago, Ill., a corporation of Illinois

Application August 27, 1938, Serial No. 79,595

Term of patent 14 years

To all whom it may concern:

Be it known that I, Herbert F. Sammons, a citizen of the United States, residing at 6708 N. Oxford Avenue, in the county of Cook, city of Chicago, State of Illinois, have invented a new, original, and ornamental Design for an Indicating Knob, of which the following is a specification, reference being had to the accompanying drawing, forming a part thereof.

Fig. 1 is a plan view of an indicating knob showing my new design.

Fig. 2 is a side elevation view of the indicating knob.

Fig. 3 is an end elevation view of the indicating knob.

I claim:

The ornamental design for an indicating knob, substantially as shown.

HERBERT F. SAMMONS.
